UNITED STATES PATENT OFFICE.

CHRISTOPHER L. ROGERS, OF SEATTLE, WASHINGTON, ASSIGNOR, BY DIRECT AND MESNE ASSIGNMENTS, TO STEPHEN M. LONG, OF SEATTLE, WASHINGTON.

BUTTONHOLE-CUTTER.

SPECIFICATION forming part of Letters Patent No. 698,142, dated April 22, 1902

Application filed June 13, 1901. Serial No. 64,359. (No model.)

To all whom it may concern:

Be it known that I, CHRISTOPHER L. ROGERS, a citizen of the United States, residing at Seattle, in the county of King and State of Washington, have invented certain new and useful Improvements in Buttonhole-Cutters, of which the following is a specification, reference being had therein to the accompanying drawings.

10 This invention relates to improvements in buttonhole-cutters, the object of the invention being to provide a simple and comparatively inexpensive cutter whereby changes may readily be made to adapt the same for cutting buttonholes of various sizes and forms; and it consists in the construction and novel combination and arrangement of parts hereinafter fully described, illustrated in the accompanying drawings, and pointed out in the 15 appended claims.

In the said drawings, where like numerals of reference indicate corresponding parts in all of the figures, Figure 1 is a longitudinal side view of the cutter, and Fig. 2 is a section through line $x'y$ of Fig. 1. Figs. 3, 4, and 25 5 are detail perspective views of parts of the invention.

The implement consists of scissors-like main portion, comprising jaws 2 and 3, pivotally connected at 4 and having handles 5, with a spring 6 interposed therebetween to keep the jaws normally apart. To the jaw 2 is attached by a thumb-screw 7 and pins 8, which register with holes 9, a blade 10, having two oppositely-disposed cutting edges 11 and 12, one of which, 11, is straight, while the other, 12, is straight a portion of its length and terminates in an eye 13 for making corresponding incisions in the cloth, as required. The other 30 jaw 3 is of a round cross-section, upon which is loosely mounted, so as to be free to rotate thereon, but prevented from moving endwise therefrom by riveting the end of the plug over a washer 19, a sleeve-die 15, having a plurality of unequally long faces 16, any one of 35 which may be rotated so as to be brought di-

rectly beneath the operative cutting edge of the aforesaid blade, the length of the face which opposes the blade regulating the length of the cut in the cloth. To hold the die to 50 any set position, I provide a plate 26, secured by a thumb-screw 17 to a flat surface on the main portion of the implement and in the same plane as that of one of the said faces of the die, and extending upwardly from this 55 plate is an offset 18, bent at right angles to form a gage-face 19, whereby the buttonholes may be cut to any predetermined distance from the cloth edge, and for this purpose the locking-plate is slotted at 20 for its adjustment, as well as having graduated teeth 21 in the implement-body for engaging with the end of the said plate.

The more important advantages of my invention are the quick manner of making 65 changes, first, as to the blade, which may be changed from a straight-slot cutter to a looped-end one, or vice versa, by simply reversing the blade itself and without the necessity of removing the die; second, the changing of 70 the blade-opposing die-face by rotating the die; third, the manner of positively securing the die to its set position, and, fourth, by providing a cloth distance-gage which is rigidly secured to the predetermined distance the 75 buttonholes are to be cut from the cloth edge.

What I claim, and desire to secure by Letters Patent, is—

1. In a buttonhole-cutter, the combination with the pivotally-connected handles and the 80 jaws, of a blade having a straight cutting edge and a cutting edge with a straight portion terminating in an eye and disposed oppositely to each other, means to secure said blade to one of the said jaws so that either of 85 the said cutting edges may be moved into and retained in operative position, and a die-sleeve having a plurality of faces rotatably mounted permanently upon the other jaw, means to lock the said die-sleeve to any set 90 position, and the cloth-gaging means.

2. In a buttonhole-cutter, the combination

with the pivotally-connected handles and jaws, of a blade having a straight cutting edge and a cutting edge with a straight portion terminating in an eye and disposed oppositely to each other, means to secure said blade to one of the said jaws so that either of the said cutting edges may be moved into and retained in operative position, and a die-

sleeve having a plurality of faces rotatably mounted permanently upon the other jaw. 10

In testimony whereof I affix my signature in presence of two witnesses.

CHRISTOPHER L. ROGERS.
